(57) **CLAIM**

The ornamental design for a bottle, as shown and described.

DESCRIPTION

FIG. 1 is a perspective view of a bottle;

FIG. 2 is a front view thereof;

FIG. 3 is a rear view thereof;

FIG. 4 is a right side view thereof, the left side being a mirror image thereof;

FIG. 5 is a top view thereof; and,

FIG. 6 is a bottom view thereof.

The stripes applied to the rear of the bottle represent opaque contrast on the rear sidewall surfaces.

The broken lines shown in the figures are for illustrative purposes only and form no part of the claimed design.
